UNITED STATES PATENT OFFICE.

LEO EISEMANN, OF NEW YORK, N. Y.

DESIGN FOR A FAN-HANDLE.

48,630.

Specification for Design.

Patented Feb. 29, 1916.

Application filed November 15, 1915. Serial No. 61,674. Term of patent 3½ years.

To all whom it may concern:

Be it known that I, LEO EISEMANN, a citizen of the United States, and a resident of the borough of Manhattan, in the city, county, and State of New York, have invented a new, original, and ornamental Design for a Fan-Handle, of which the following is a specification, reference being had to the accompanying drawing, forming a part thereof.

Figure 1 is a plan view and Fig. 2 an edge view of the handle, showing my new design.

I claim:

The ornamental design for fan handle, as shown.

LEO EISEMANN.
